UNITED STATES PATENT OFFICE.

JONATHAN SHERMAN, OF NORTH WINTERPORT, MAINE.

SCREW-PROPELLER.

SPECIFICATION forming part of Letters Patent No. 359,103, dated March 8, 1887.

Application filed October 11, 1886. Serial No. 215,900. (No model.)

To all whom it may concern:

Be it known that I, JONATHAN SHERMAN, of North Winterport, in the county of Waldo, of the State of Maine, have invented a new and useful Improvement in Propellers for Navigable Vessels; and I do hereby declare the same to be described in the following specification, and represented in the accompanying drawings, of which—

10 Figure 1 is a top view, and Fig. 2 a perspective view, of a propeller embodying my invention, the nature of which is defined in the claim, hereinafter presented. Fig. 3 is an edge elevation of one of its wings or paddles.

15 In my improved propeller each of its wings or paddles A consists of a rectangular plate bent lengthwise to an ogee or cyma form, as represented, and fixed at its central part to an arm, B, projecting from a head, C, at one end thereof, such arm being bent lengthwise of it in manner as represented, and arranged obliquely to the axis of the head. The blade, by having the arm attached to it at its central part and not at either edge of such blade, stands with 25 its surface at or about at right angles to the arm both lengthwise and transversely of such blade. The arm, therefore, does not extend from any part of the edge of the blade and in 30 a line with the blade transversely or longitudinally thereof, as shown in either of the United

States Patents No. 2,825 and No. 4,441. On this propeller being revolved in one direction when immersed in water and extended from the stern of the hull of a navigable vessel, and applied to a revoluble shaft, as screw-propellers usually are, it will advance the vessel; but on being revolved the opposite way it will effect a backward movement of such vessel. 35

In practice I have found it very effective and in several respects quite as if not more 40 efficient than ordinary screw-propellers as commonly made and used.

I do not claim a propeller having cyma-shaped wings fastened at their edges to arms projecting from a hub, all being as shown in the 45 aforesaid United States Patents.

I claim—

The improved propeller, substantially as described, constructed with each of its wings or blades cyma-shaped and so connected at its 50 central part with its supporting-arm as to cause such arm to project at or about at right angles from one face of such wing or blade and obliquely to the axis of the hub, essentially as represented.

JONATHAN SHERMAN.
